by

UNITED STATES PATENT OFFICE.

WENDELL P. KEENE, OF BROOKLYN, NEW YORK, ASSIGNOR TO UNDERWOOD TYPE-WRITER COMPANY, OF NEW YORK, N. Y., A CORPORATION OF DELAWARE.

LEDGER-SHEET.

1,357,638.

Specification of Letters Patent.

Patented Nov. 2, 1920.

Application filed April 18, 1919. Serial No. 290,969.

To all whom it may concern:

Be it known that I, WENDELL P. KEENE, a citizen of the United States, residing in Brooklyn borough, in the county of Kings, city and State of New York, have invented 5 certain new and useful Improvements in Ledger-Sheets, of which the following is a specification.

This invention relates to bookkeeping devices, especially such as are adapted to be used for bank bookkeeping, and is herein illustrated as applied to a loose-leaf "Boston" ledger, especially adapted to be used in connection with an Underwood standard 15 bookkeeping machine.

"Boston" ledgers comprise sheets which have a horizontal ruling to divide them into spaces, so that there is a horizontal space between each two lines of ruling for each 20 account on the ledger. These ledger sheets are also provided with vertical rulings to divide the horizontal spaces into columns for days, a column or columns for names, and other minor columns. Each day column is 25 usually further divided into other columns, herein shown as four subsidiary columns, one to receive checks or charges, one to receive deposits or credits, one to receive daily balances, and one to receive a pick-up column for use in computing the daily balance. 30

Since each subsidiary column has to receive an entry or a daily balance, which may be of considerable magnitude, a weekly sheet with all these ruled columns on it is of considerable width, making it awkward to handle as well as difficult to adjust properly and rapidly around the platen of a typewriting machine. Moreover, typewriting or other computing machines having a carriage sufficiently long to accommodate a work-sheet 40 of this width are awkward and noisy in operation, and require a great deal of space to permit the travel of the carriage. Besides this, they are expensive to build.

According to the present invention, to enable the balances to be conveniently and yet accurately transferred from one sheet to the next, or from one side of the sheet to the other side of the sheet, the sheet may be provided with margins adapted to be folded over in such a way as to receive a copy of the daily balance column of the last day on either side of the sheet, so that the margins may be afterward detached or turned over to

enable the daily balance for the following 55 day to be inserted in the proper column for that day by direct copying. The ledger sheet may accommodate half of a week instead of a week upon each face, thus bringing the sheet within limits, which makes it convenient to handle in connection with a typewriting machine. Between the margin and the adjacent one of the day columns, suitable 60 perforations or cuts may be made in the sheet to enable it to be used in a loose-leaf 65 binder.

Other features and advantages will herein-after appear.

In the accompanying drawings,

Figure 1 is a perspective view of a ledger 70 embodying one form of sheet constructed according to the present invention.

Fig. 2 is a face view of a sheet showing the side for the first half of a week.

Fig. 3 is a similar view showing the other 75 side of the sheet, that is, the one for the last half of the week.

Fig. 4 is a diagrammatic perspective view, showing the sheet with the Fig. 2 face out, and folded and inserted around the platen 80 of a typewriting machine.

Fig. 5 is a face view of the right-hand margin seen in Fig. 2 as detached and turned around to enable the balances to be copied therefrom.

Fig. 6 is a perspective view similar to Fig. 4, but showing the other face of the sheet, after the margin of Fig. 5 has been detached.

Fig. 7 is a view of the right-hand margin of Fig. 3 detached, and turned around after 90 the Saturday entry was made, to enable the balances to be copied off therefrom.

In beginning a new sheet, as, for example, in copying from an old style hand-written ledger, the loose-leaf sheet 20 is passed 95 around the platen 21 of a machine, such as a typewriting machine, which includes a carriage member 22, so that the face 23 of the sheet is outward, and the left-hand flap 24 and the right-hand flap 25 are folded behind 100 the body of the sheet along the lines 26 and 27. Usually, the names of the depositors are already printed in the name column 28.

Usually at the beginning of the day or at the close of the previous day's business, the 105 first daily balance entry is in the daily balance column 29 for that day, and is written in green ink. When a check or checks to-

taling \$75.00 comes to the typist's desk, the typist positions the typewriter carriage 22, so that it will write in the pick-up column 30, and copies into that column the last 5 entry in the daily balance column, viz., \$250.75, opposite the name "John Doe." This is added in the usual way in a so-called "computing" register often found in machines of the type of the Underwood standard bookkeeping machine. Then the typist brings the typewriter carriage to write in the checks-column 31 and enters therein, in black, the item of \$75.00 for the checks which have come to the typist, he having 10 previously set the mechanism to subtract from the "computing" register and to add in a checks "totaling" register. The typist then brings the typewriter carriage to write in column 29 and copies out the total now 15 shown in the "computing" register, namely, \$175.75, subtracting it from that register, and bringing it to zero. Then the typist depresses the usual star-key to print the star shown at 32, thus proving that the 20 copying from the "computing" register was correctly done.

In order to facilitate the operation of bookkeeping, and to minimize the handling of the sheets, it is customary to separate the 25 charge and credit memoranda, checks, etc., that come to the typist's desk, so that ordinarily the typist will be only entering charges at one part of the day, or one part of an hour of the day, and will be only 30 entering credits the remainder of the time. Thus it happens that in most accounts there will appear on the ledger only one credit and one debit item each day, unless checks are sent in for collection, or deposits are 35 made at widely separated intervals during the day. For this reason only a single check or debit entry is herein illustrated.

For the same reason a single credit entry or deposit is illustrated as being the next 40 item, amounting to \$125.50. Before entering this item, the typist brings the typewriter carriage again to write in column 30 and adds in the "computing" register \$175.75, which forms the last entry in the daily 45 balance column. Then the typist brings the typewriter carriage to write in the deposits-column 33 and writes therein, in black, that item, adding it both in a deposits or credit register and in the aforesaid "computing" 50 register, with the result that the "computing" register shows the total \$301.25. Then the typist copies this total shown in the "computing" register into column 29, subtracting it from the "computing" register, 55 thus bringing that register to zero. Then the typist prints a star like the star 32 to prove the accuracy of copying from that register. Usually this closes the business in that account for the day.

60 65 At the close of the day's business, it is

customary to copy out the daily balances into the daily balance column 34 of the following day, at the same time footing all the daily balances thus copied, with the result that the total thus obtained may be used in proving the accuracy of the day's work.

When Wednesday is reached, the margin or flap 25 is utilized to obtain a carbon copy of the daily balance column 35 of Wednesday, and for this purpose there is inserted, 75 as shown in Fig. 4, a carbon-sheet 36 between the folded-over margin 25 and the main body of the sheet 20, said margin extending far enough to the left to exactly cover the whole of the daily balance column 80 35, with the result that the entries in the Wednesday daily balance column 35 will be shown in a carbon copy as illustrated in the Wednesday transfer balance column 37, shown in Fig. 5. This margin at the close 85 of business Wednesday may be detached along the perforated line 27, and copied into the daily balance column 38 on the opposite face of the sheet. For this purpose, the sheet is inserted as shown at Fig. 6, and the 90 transfer balance copied into the daily balance column 38 for Thursday.

It will be noted that the daily balance columns 34, 35 and 38 are all copies of the final daily balance on Monday as shown in the 95 daily balance column 29. This is due to the fact that the accounts are inactive on those days. These entries in columns 34, 35 and 38 are consequently all made in green ink. For the same reason the entries are made in 100 green ink in the daily balance column 39 for Friday, and the daily balance column 40 for Saturday.

In order to enable the Saturday balances which close the week to be copied out just 105 as the Wednesday balances were copied out, there is inserted a carbon-sheet 41 between the folded-over margin or flap 24 and the body of the sheet, adapted to cause the entries of the Saturday daily balance column 110 to be copied into the Saturday transfer balance column 42, as shown in Fig. 7, upon the margin 24. Thus, when the margin 24 is detached along the line 26, it can be readily used for copying off the daily 115 balances, which are the only final significant entries onto the opposite face of the sheet in Monday's column. When both margins are thus detached, the leaves, when bound into the loose-leaf book, present the appearance 120 shown in Fig. 1.

It will be noted that the name columns 43 and 44 come at the outer margins of the sheets when held by the binder, diagrammatically shown at 45, and which co-operates 125 with projections formed by such openings as are shown at 45^a on the line 27. This enables the typist or other person turning over the sheets to pick out a sheet containing the desired names with the utmost rapidity. 130

In order to enable the margin to be used for the transferring described above with the utmost celerity and accuracy, the usual "line number" columns 46 at the sides of the sheet, which serve to guide the eyes of the bookkeeper, are reproduced in columns 47 and 48 upon the faces of the margins 24 and 25 from which the copying is to be done, thus enabling the typist in copying off the daily balances to check up the accounts by their alined numbers.

It will be seen that in this form of sheet there is provided a page which need not exceed 19 or 20 inches in width, and which is therefore convenient to handle, and which is adapted to receive in the most convenient manner which will enable them to be accurately verified, since the footings of the active 20 checks-column of every sheet and the footings of the active deposits-column of every sheet enable any error occurring therein to be instantly located in one or the other of these columns. Moreover, the bound book 25 of sheets is conveniently compact for storage and easily handled. The sheets may be such as may be easily handled by the typist in the kind of loose-leaf ledger shown in the patent to Kidder, 1,223,075.

In addition to the columns and rulings described above, there is also a horizontal ruling forming a space 49 for totals at the bottom of each sheet. By footing up these totals of each sheet separately, it becomes 30 possible to locate, upon the proper sheet, errors in transferring from one column to another upon the sheet, thus enabling the sheet to become part of an elaborate system for the rapid location of errors from several 35 points of view.

Variations may be resorted to within the scope of the invention, and portions of the improvements may be used without others.

Having thus described my invention, I

45 claim:

1. A ledger-sheet for a printing and computing machine, but wider than the carriage thereof, and comprising a name-column printed near one margin, three appropriately designated day-columns forming the body of the sheet on one face for one-half the week, three appropriately designated day-columns upon the other face for the other half of the week, the other margin 50 of the sheet comprising openings adapted to coöperate with a binder, and a margin beyond said openings adapted to receive a carbon copy of the entries of one column near the margin, said margin adapted to be

folded to enable the sheet to enter the carriage.

2. A ledger-sheet for a printing and computing machine, but wider than the carriage thereof, and comprising margins adapted to receive a carbon copy of entries on the ledger-sheet, and comprising appropriately designated day-columns, each day-column comprising a charge-column, a credit-column, a daily balance-column, and a pick-up-column, fold lines along which said sheet 70 is adapted to be folded to enable it to enter the carriage, said sheet adapted to coöperate with a binder along one of said fold lines, and a margin beyond said fold lines adapted to receive a carbon copy of the entries in 75 the daily balance-column.

3. A ledger-sheet for a printing and computing machine, but wider than the carriage thereof, appropriately designated day-columns upon each face of said sheet, subsidiary columns under each day-column including a charge-column, a credit-column, a daily balance-column, and a pick-up-column, fold lines upon which the margins are adapted to be folded to bring the sheet 80 within the limits of the carriage, said margins adapted to extend over and terminate at the adjacent daily balance-column when folded and to receive a carbon copy thereof, line-number-columns lying outside of each 85 end of the day-columns, and a line-number-column upon each margin to facilitate the rapid reading of the margin.

4. A ledger-sheet for a printing and computing machine, but wider than the carriage thereof, appropriately designated day-columns upon each face of said sheet, subsidiary columns under each day-column including a charge-column, a credit-column, a daily balance-column, and a pick-up-column, fold lines upon which the margins are adapted to be folded to bring the sheet 90 within the limits of the carriage, said margins adapted to extend over and terminate at the adjacent daily balance-column when 95 folded and to receive a carbon copy thereof, line-number-columns lying outside of each end of the day-columns, a line-number-column upon each margin to facilitate the rapid reading of the margin, said margins being 100 detachable along the fold lines, and devices to coöperate with a binder at one of said fold lines.

WENDELL P. KEENE.
